DEFLECTOR MEANS

Daniel H. Prutton, Cleveland, Ohio

Application July 12, 1937, Serial No. 153,216

8 Claims. (Cl. 230—274)

This invention relates to improvements in deflector means for changing the direction of flow from air delivery means.

One of the objects of the present invention is to provide a novel deflector means for causing an oscillation of the air currents delivered from a fan means or the like.

Another feature of the present invention is the novel arrangement of a deflector means by which a stream of air is directed in varying conoidal forms having a common axis.

Another feature of the present invention is the provision of oscillating air streams from a piece of fan equipment, wherein no moving parts are visible.

Another object of the present invention is to provide an oscillating stream of air by means of novel deflector means having few operating parts very simply arranged.

Another object of the present invention is the provision of a casing having air delivery means for discharging air at one end of the casing and a diaphragm supported in spaced relation to the delivery end of the casing, together with means for varying the position of the diaphragm so as to vary the angle of the air stream deflected by it.

Other novel features of the invention will be apparent from the accompanying drawings and description and the essential features will be summarized in the claims.

In the drawings, Fig. 1 is a central section through one embodiment of a fan means combined with my improved deflector means; Fig. 2 is a view similar to Fig. 1 showing another position of the parts; Fig. 3 is a detail view showing a portion of the driving connection between the motor and the deflector means; Fig. 4 is a sectional view along the line 4—4 of Fig. 1, showing the arrangement of the driving mechanism between the motor and the deflector means; Fig. 5 is a sectional view through a modified form of apparatus; Fig. 6 is a top plan view of another modification; while Fig. 7 is a sectional view along the line 7—7 of Fig. 6.

While my invention is applicable to various shaped devices equipped with various air moving means, I have illustrated in Fig. 1 a casing 10 circular in section and supporting by the web 11 a motor 12 having a shaft 13 which drives fan 14 so as to propel a stream of air upwardly past the motor and out the upper end of the casing. The lower end of the casing is provided with air inlet openings 15 or the casing might be elevated on legs for the purpose of providing an air inlet.

The entire device here shown is adapted to be placed upon the floor or upon a table, but other applications of my invention will occur to those skilled in this art.

Positioned transversely of the casing at the air delivery end thereof is a diaphragm 16 which is preferably flexible and may be made of rubber, leather or the like. This diaphragm is supported centrally on the rod 17 and is supported at its periphery by the cap member 18 so that the periphery of the diaphragm is in spaced relation to the delivery end of the casing 10. To this end the cap member 18 is supported by spaced members 18a. This provides an annular opening 19 between the periphery of the diaphragm and the delivery end of the casing 10. If desired the casing may have the reentrant curve as shown at 10a so that the discharge lip 20 has a directing effect upon the delivered current of air. The cap member as shown may be provided with a centrally raised portion 21 for accommodating the movement of rod 17 and may have an insert member 22 suitably secured to the cap member as by spot welding or the like, this member having a central opening 22a for guiding the rod 17. The diaphragm is secured at its periphery to the cap 18 by any suitable means, as for instance by the ring 23 which is preferably secured to the cap so as to permit a replacement of the diaphragm if necessary. The cap 18 is upwardly convex as shown in Fig. 1, although other forms of cap may be used to obtain similar results.

Means is provided for varying the position of the diaphragm so as to change the direction of the air current delivered through the opening 19. In the form shown in Fig. 1, the central portion of the diaphragm is moved upward and downward so as to move the diaphragm alternately between the positions shown in Figs. 1 and 2, thus delivering the air in conoidal forms as indicated by the arrows in these figures. In Fig. 1 the air stream is delivered in substantially conoidal form upwardly as indicated by arrows 24, and in Fig. 2 downwardly as indicated by arrows 25. In other words, the direction of the deflected air stream is at angles to the central axis of the casing extending radially outwardly with the angles varying during the operation of the device. In the form shown in Figs. 1 and 2, this deflection of the air currents is radially outward from the central axis in all directions and the angle of the deflected air stream to the central axis varies from an inclination away from the delivery direction of the main air stream as in Fig. 1 to a position where the angles are inclined backward-

ly toward the delivery direction of the air stream as shown in Fig. 2. It will be noted that the various conoidal forms of the deflected air stream have a common axis, namely, the central axis 5 of the casing. As shown in Fig. 1, the diaphragm 16 approaches a position parallel to the mouth 20 of the casing 10 and in the position of Fig. 2, it approaches a position parallel to the convex cap member 18, thus giving a well defined direction to 10 the deflected air stream.

While other means might be used to cause the movement of the diaphragm just described, I prefer to utilize the motor 12 for this purpose. As indicated in Figs. 1 and 3, a rotating fan of 15 the usual self-oscillating type may be adapted for this use. One such type of fan utilizes the motor shaft 13 to drive a worm 26 which in turn drives a worm gear 27 on shaft 28. On this shaft is a second worm 29 driving a worm gear 30 on 20 shaft 31 which is at 90° to the motor shaft as indicated. In the ordinary oscillating fan this shaft has an eccentric as indicated at 32 having a pin 33 utilized to oscillate the fan. In the present instance I connect pin 33 by a connecting rod 34 with a pin 35 which is rigidly connected to the lower end 17a of the rod 17. The portion 17a is slidably mounted in a member 36 which is rigidly supported on the motor casing. This is provided with a slot 36a for the 30 accommodation of pin 35 during its oscillation in a vertical plane. Preferably the shaft 31 is extended in both directions as indicated at 31a and provided with a second eccentric 32a with connecting parts as indicated similar to those 35 just described with the suffix *a* so as to provide driving means for the rod 17 on opposite sides thereof to prevent any binding of the parts.

In the operation of the device of Fig. 1, the 40 motor is supplied with current from a suitable source not shown. The fan delivers a current upwardly within the casing 10 and the operative connections between the motor and rod 17 cause a movement of the central portion of the diaphragm between the positions of Figs. 1 and 45 2 alternately so as to vary the deflected current of air between the positions shown by the arrows.

In Fig. 1 I have shown a diaphragm having a 50 fixed periphery and a movable central portion but it is possible to obtain a similar effect by fixing the central portion and moving the periphery. This modification is shown in Fig. 5 where the parts similar to Figs. 1 and 2 have been similarly designated. In this case a cap member 55 18' supports the diaphragm 16 at the central point 37 as by means of spaced supporting members 18a secured to the casing 10. The periphery of the diaphragm is secured to a sleeve member 38 open around a major portion of the top side walls as indicated at 38a. The connecting rods 34 and 34a are connected to the sleeve member 38 as indicated. It will be obvious that operation of the motor will cause the diaphragm to move between the full line and broken line 60 positions of Fig. 5, resulting in a variation in the deflected stream of air as indicated by the full and broken line arrows.

In Figs. 6 and 7 is shown another modification 70 wherein the casing is substantially semicircular in section or at least the discharge end is substantially semicircular. Here again the parts similar to those in Fig. 1 have been given similar reference characters. The difference here is that the diaphragm 39 is substantially semicircular in form and preferably closely corresponds

to the cross section of the casing. The cap member 40 may be formed by extending one of the side walls of the casing upwardly as at 40a and then bending the same over the top 5 of the casing as indicated. Supporting members may be supplied at 40b if desired. The diaphragm is secured to the cap member 40 by the strip 41 extending from point 42 to point 43 about the arcuate side of the casing provided with the opening 44. The portion of the diaphragm next to the wall 40a is not fastened. Here again the central portion of the diaphragm at 45 is secured to the rod 17 which in turn is supported for reciprocating movement by the brackets 46 carried by the casing. In this form 15 of device, upon operation of the motor the diaphragm is oscillated between the full line and broken line positions of Fig. 7, causing the deflected air currents to take the directions indicated, varying between the two sets of arrows 20 shown and extending in semicircular distribution about the top of the casing.

It will be noted that my improved device 25 delivers an oscillating current of air in a novel manner without any visible moving parts and with a very light load upon the motor for the operation of the deflector means.

What I claim is:

1. In combination, a casing, means for delivering an air stream at one end of said casing, a 30 flexible diaphragm in said delivered air stream having a peripheral support and a central support, the periphery of said diaphragm being spaced from the said one end of said casing, and means for moving one of said supports in the 35 direction of air stream delivery whereby to vary the deflecting angle of said diaphragm.

2. In combination, a casing, air moving means within the casing for delivering a stream of air at one end thereof, a flexible diaphragm having 40 its periphery held in spaced relation to the delivery end of said casing, and means for moving the central portion of the diaphragm endwise of the casing, whereby to vary the angle 45 of the air delivered in the space between said diaphragm and casing.

3. In combination, a casing, air moving means within the casing, a flexible diaphragm having 50 peripheral and central supports, the periphery of said diaphragm being held in spaced relation to the delivery end of said casing, and means for moving the periphery of the diaphragm toward and from the end of the casing to vary the angle 55 of the air stream there delivered.

4. In combination, a casing substantially 55 semicircular at its delivery end, air moving means within the casing, a flexible diaphragm having a semicircular periphery supported in spaced relation to the corresponding delivery end of the casing, and means for moving the 60 central portion of the diaphragm endwise of the casing.

5. In combination, a casing, a motor supported within said casing, fan means driven by said motor for delivering air at one end of said casing, a diaphragm transversely of said casing end having a central support and a peripheral support maintaining the periphery of said diaphragm spaced from the delivery end of said casing, eccentric means driven by said motor, 70 and an operative connection between said eccentric means and one of said supports for moving the said one support endwise of the casing to vary the angle of said diaphragm as it deflects 75 the delivered air stream.

6. In combination, a casing, a motor supported within said casing, fan means driven by said motor for delivering air at one end of said casing, a diaphragm transversely of said casing end having a central support and a peripheral support maintaining the periphery of said diaphragm spaced from the delivery end of said casing, and means driven by said motor having an operative connection with one of said supports for moving the said one support endwise of the casing to vary the angle of said diaphragm as it deflects the delivered air stream.

7. In combination, a casing, means for delivering an air stream at one end of said casing, a flexible diaphragm having its periphery held in spaced relation to at least a portion of said one end of said casing, and means for flexing said diaphragm to vary its effect upon the air

stream delivered through said space between said diaphragm and casing.

8. In combination, a hollow casing adapted to rest upon a supporting surface with the passageway therethrough in vertical position, a motor and a fan driven thereby in said casing adapted to deliver a stream of air out the upper end of said casing, there being air inlet openings in said casing, a flexible diaphragm supported across the upper end of said casing with at least a portion of the periphery of said diaphragm spaced from the end of said casing, and an operative connection between said motor and said diaphragm for flexing the latter to vary its effect upon the air stream delivered through the space between said diaphragm and casing.

DANIEL H. PRUTTON.
